INVENTOR,
Joseph Mersman,
BY
Howard A. Smith.

His ATTORNEY.

UNITED STATES PATENT OFFICE.

JOSEPH MERSMAN, OF OTTAWA, OHIO.

SOUND-MODIFYING APPARATUS.

Application filed February 18, 1921. Serial No. 446,057.

To all whom it may concern:

Be it known that I, JOSEPH MERSMAN, a citizen of the United States, residing in the town of Ottawa, in the county of Putnam 5 and State of Ohio, have invented a certain new and useful Improvement in Sound-Modifying Apparatus, of which the following is a specification.

The principal object of my invention is 10 to provide a new and improved method of resonating or intensifying reproduced tones. When tones are reproduced by a vibrating elements, added force may be given to those tones by causing the molecules of air 15 set in motion by the vibrating element to impinge on other bodies which, if they are similar to said vibrating element, will vibrate in harmony with the latter to set additional molecules of air in motion to intensify 20 or amplify the sound originally reproduced. Therefore, my method effects the resonance of reproduced tones, by interposing in the path of the molecules of air set in vibration by the reproducing element, vibrating me- 25 diums of the same nature as the reproducing element. These mediums, then, will be caused to vibrate in perfect harmony with the reproducing element to set in motion additional molecules of air to produce pure 30 tones in greatly increased volume.

My improved means for carrying out this method of adding force to reproduced tones, while applicable to all sound producing instruments, is particularly adapted for use 35 in phonographs or talking machines. It is well known that, due to inequalities in the running of the grain of wood in the amplifiers of talking machines, pure tones are only produced in some of them. This is 40 due to the fact that the molecules of air set in motion by the diaphragm in the sound box, when they strike the sides of an amplifier in which the grain of wood is not the same, set up unequal vibrations. My im- 45 proved means, therefore, for producing pure tones in a talking machine, contemplates the mounting in a resonating tube combined with the reproducer, of secondary dia- 50 phragms of the same size and thickness as the diaphragm in the sound box. When struck by the molecules of air set in motion by the reproducing diaphragm, and each other, these secondary diaphragms will vi- 55 brate in perfect harmony with the repro- ducing diaphragm in the sound box to set in motion additional molecules of air to

produce pure tones in greatly increased volume.

My improved resonating means also make the talking machine containing them, imper- 60 vious to moisture, since the secondary dia- phragms in the resonating tube will re- spond as freely to the impinging molecules of air on damp days as on dry days. Ampli- 65 fiers made of wood, however, when damp or wet, will not respond with the same free- dom to the impinging molecules of air set in motion by the reproducing diaphragm, as when dry.

Other important and incidental objects 70 will be brought out in the following speci- fication and particularly set forth in the subjoined claims.

In the accompany drawings, Figure 1 is a top plan view of my combination resonator 75 and reproducer, partly broken away to show one of the secondary diaphragms. Figure 2 is a side elevational view thereof, also partly broken away to show one of the sec- 80 ondary diaphragms. Figure 3 is a plan view of the first secondary diaphragm. Figure 4 is a plan view of the second secondary diaphragm. Figure 5 is a plan view of the third secondary diaphragm. And Figure 6 is a cross sectional view taken through one 85 of the secondary diaphragms.

Throughout the specification and draw- ings, similar reference characters denote corresponding parts.

Referring to the accompanying drawings, 90 the numeral 1 designates a turntable upon which is mounted a record 2. Resting upon the latter is the stylus 3 of a sound box 4 that contains a reproducing diaphragm 5. The sound box 4 is connected by a hollow 95 neck piece 6 to a resonating tube 7 pref- erably constructed as follows:

Referring to Figures 1 and 2, the reso- 100 nating tube 7 consists of a hollow cylinder constructed of any suitable material pref- erably closed at its rear end by a head 8. Mounted progressively in the resonating tube 7 are three secondary diaphragms 9, 10 and 11 respectively, each of which is preferably constructed as follows:

Referring to Figure 6, each secondary dia- 105 phragm consists of a disc 12 containing a central hole 13. Resting upon a gasket 13^a of soft material that bears against the marginal face portion of the disc 12, is a 110 disc 14 preferably constructed of mica or of a material similar to that of which the

diaphragm 5 is composed, and approximating it in size and thickness. Bearing against the disc 14 is an annular gasket 15 composed of a soft material, and pressed against said disc by a ring 16. The latter and the disc 12 are connected by screws 17 to firmly compress the gaskets against the disc 14.

The secondary diaphragm 9 (see Figure 3) which is set in the front portion of the resonating tube 7, as shown in Figures 1 and 10, preferably has a hole 13 smaller in diameter than the hole 13 in the secondary diaphragm 10 which is set behind the diaphragm 9 in the resonating tube 7, while the 15 hole 13 in the last named diaphragm is smaller than that in the secondary diaphragm 11 which is mounted in the end portion of the resonating tube 7.

Provided in the top portion of the periphery of the resonating tube 7 in front of each 20 of the diaphragms 9, 10 and 11, are three apertures 18, although a greater or less number may be provided if desired. (See Figures 1 and 2.) Through these apertures the 25 resonated tones pass outside the tube.

The resonating tube 7 is pivotally secured on a forked standard 19 by means of set 30 screws 20, 20. The standard 19 is in turn supported by a base block 21. The latter is readily moved over the table 1 to an adjusted position, while the standard 19 may be turned in the hole in the block 21 which receives it, to permit the stylus 3 to have a free lateral movement. It may be freely 35 raised and lowered by reason of the pivotal support which the standard 19 affords the resonating tube 7.

When the diaphragm 5 in the sound box 4 is vibrated by the stylus 3, it will set in 40 motion molecules of air that will travel through the neck piece 6 into the resonating tube 7 to impinge against the disc 14 in the diaphragm 9, causing it to vibrate in har-

mony with the diaphragm 5 and to set in motion additional molecules of air which 45 pass through the small hole 13 in said diaphragm to impinge against the disc 14 in the diaphragm 10. This causes the latter to vibrate in harmony with the first two diaphragms, and to set in motion additional 50 molecules of air which travel through the larger hole in said diaphragm to strike the disc 14 in the diaphragm 11 in the rear portion of the resonating tube 7, causing it to vibrate in unison with the other discs 55 and to set in motion additional molecules of air. As stated in the beginning, the harmonious vibration of these secondary diaphragms will produce pure tones in greatly increased volume. These tones are emitted 60 through the sound apertures 18, whose number and size may be greater or less than shown.

Having described my invention, I claim:

1. The combination with a reproducer, of 65 a resonating tube, and vibrating elements mounted in said tube in the path of the molecules of air set in motion by the reproducer, said tube having apertures provided in its periphery in proximity to the vibrating elements for the purpose specified.

2. The combination with a reproducer, of 75 a resonating tube, a diaphragm contained in the reproducer, and a series of diaphragms mounted in said resonating tube, said diaphragms being approximately similar in size, thickness and texture to the diaphragm in the reproducer to vibrate in harmony with the diaphragm in the reproducer for the purpose specified.

In testimony whereof I have hereunto set my hand this 16th day of February, 1921.

JOSEPH MERSMAN.

Witness:

HOWARD S. SMITH.
